UNITED STATES PATENT OFFICE.

DAVID WALKER, OF NEWARK, AND FRANK. H. HOWARD, OF IRVINGTON,
NEW JERSEY.

DESIGN FOR A STAIR-CARPET FASTENER.

SPECIFICATION forming part of Design No. 19,973, dated July 1, 1890.

Application filed May 16, 1890. Serial No. 352,092. Term of patent 14 years.

To all whom it may concern:

Be it known that we, DAVID WALKER and FRANK. H. HOWARD, citizens of the United States, residing at Newark and Irvington, respectively, in the county of Essex and State of New Jersey, have invented and produced a new and original Design for Stair-Carpet Fasteners; and we do hereby declare the following to be a full, clear, and exact description of the invention, such as will enable others skilled in the art to which it appertains to make and use the same, reference being had to the accompanying drawings, and to letters of reference marked thereon, which form a part of this specification.

Referring to said drawings, Figure 1 represents a plan view of a stair-carpet fastener, showing our design. Fig. 2 is a central longitudinal section through line *x*, and Fig. 3 is a central transverse section through line *y* of said Fig. 1.

These several views are deemed necessary or sufficient to fully illustrate our design, the leading feature of which consists in a six-pointed star-shaped figure raised upon a plate

a, which is bent through the center longitudinally at a right angle and has a perforation at the center, where the several points of the star-shaped figure converge, as will be understood by reference to Figs. 1 and 3. The outer edge or rim of said plate may be scalloped or curved in any desired form, as indicated in the several figures of the drawings.

What we claim is—

The design for a stair-carpet fastener herein shown and described, the same comprising a plate *a*, bent longitudinally at a right angle and having a star-shaped figure raised thereon and a perforation at the center where the several points of the star-shaped figure converge, as set forth.

In testimony that we claim the foregoing we have hereunto set our hands this 10th day of May, 1890.

DAVID WALKER.
FRANK. H. HOWARD.
